Term of patent 14 years

(Cl. D2—231)

FIG. 1

FIG. 2

FIG. 3

FIG. 4

FIGURE 1 is a front elevational view of a helmet embodying my new design;

FIGURE 2 is a rear elevational view thereof;

FIGURE 3 is a view of the helmet turned up-side down to more clearly show the fin structure thereof; and,

FIGURE 4, is a view taken in the direction of the arrows 4—4 of FIGURE 1 to illustrate more clearly the fin structure.

The essential features of my design reside in the portions shown in the full lines on the drawing.

I claim:

The ornamental design for a helmet, substantially as shown and described.
